(57) **CLAIM**

The ornamental design for an end table with USB ports and outlet, as shown and described.

DESCRIPTION

FIG. 1 is a top, left and front side perspective view of an end table with USB ports and outlet, showing my new design; FIG. 2 is a top, right and back side perspective view thereof; FIG. 3 is a front elevational view thereof; FIG. 4 is a back elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines shown in the FIG. 8 illustrate portions of screws of the end table with USB ports and outlet that form no part of the claimed design.
